UNITED STATES PATENT OFFICE

FREDERICK S. McCULLOUGH, OF EDGEWOOD, PENNSYLVANIA

THERMIONIC TUBE AND CIRCUITS FOR THE SAME

Application filed January 5, 1926. Serial No. 79,353.

This invention relates to thermionic tubes and to circuits therefor, and more particularly to a tube and circuit of the indirectly heated cathode type.

5 It has heretofore been proposed to provide radio tubes having a relatively large cathode area wherein the cathode is generally of a substantially cylindrical form, and wherein it is heated by means of a centrally disposed heater wire within the cathode, it having been proposed that such wire be embedded in porcelain or other refractory material, about which the cathode is supported.

10 In tubes of this character, there is no appreciable potential gradient along the cathode, as there is in the usual hot filament cathode type of tube.

15 For this reason, such tubes in operation have a rather large grid current, which is not always desirable, and the characteristics of the tube are not the same as the characteristics of a tube of the hot filament cathode type.

20 According to the present invention, it is proposed to provide a tube of the indirectly heated cathode type, wherein means is provided for impressing different potentials at different points on the cathode, so as to render it non-equi-potential, whereby the characteristics of the tube may be more readily controlled, and the magnitude of the grid currents effectively reduced without requiring excessively high biasing batteries.

25 The invention may be readily understood by reference to the accompanying drawing which illustrates diagrammatically one embodiment of the invention, it being understood that the drawing is diagrammatic, and merely illustrative of one embodiment of my invention, and that various changes and modifications are within the contemplation thereof.

In the drawing:

30 The figure represents diagrammatically a thermionic tube embodying the invention and a portion of a circuit therefor.

35 Referring to the drawing, 2 designates a suitable envelope which may be evacuated, and within which is a plate electrode or anode 3, a control electrode 4, and a cathode struc-

ture designated generally as 5. The cathode structure includes a cathode member 6, which is preferably of cylindrical form and which may have a surface coating of a suitable material, adapted to sustain electron emission at relatively low operating temperatures. Within the cylindrical cathode member 6 is a suitable heater wire 7. This heater wire may be raised to incandescence, or to suitable temperature by means of an alternating or a direct current applied across the terminals thereof, according to the usual practice with tubes of this type.

40 Connected with one end of the cathode member 6 is a lead wire 8, which is connected with the plate electrode 3 through a suitable source of a direct current potential, such as the "B" battery 9. This battery has its negative pole connected to the cathode in the usual manner, and its positive pole connected with the plate 3. Connected with the opposite end of the cathode member 6 is a second lead wire 10, which may be connected with the grid or control electrode 4 through a control battery 11. The battery 11 will preferably have its positive side connected with the cathode 6 and its negative side connected with the grid.

45 It will thus be seen that the battery 11 applies a positive potential at one end of the cathode while the battery 9 applies a negative potential at the other end thereof, whereby the cathode 6 is rendered non-equi-potential.

50 With an arrangement as thus described, the cathode is effectually rendered non-equi-potential, and the tube may, in operation, approach more nearly the characteristics of a tube of the hot filament type.

55 By proper adjustment of the potential at 11, the operation of the tube may be controlled, and with the arrangement as thus provided, the magnitude of the grid current may be decreased or its effect minimized, without excessively large biasing voltages.

I claim as my invention:

55 1. In an electric circuit, a thermionic tube having a plate, a grid and an elongated cathode of the indirectly heated type, a source of current having its positive pole connected to the plate and its negative pole connected to one end of the cathode, and a

second source of direct current having its positive pole connected to the opposite end of said cathode and its negative pole connected to the grid.

- 5 2. In a vacuum tube circuit employing a vacuum tube having an elongated indirectly heated cathode, a grid and a plate, a connection between the plate and one end of the cathode including a source of direct current, 10 a connection between the grid and the other end of the cathode, said connection including a source of direct current the polarity of which is reversed as regards the cathode with respect to the first.
- 15 3. The combination with a thermionic tube of the indirectly heated cathode type having an elongated cathode structure and having a plate electrode, of a plurality of direct current sources connected to the cathode at separated points and so arranged as to cause a current flow of small magnitude along the cathode during the operation of the tube to thereby render the cathode non-equi-potential.
- 20 4. A thermionic tube having an elongated cathode, a heating means associated therewith within the tube and also having a control and plate electrode, a source of direct current connected across one end of the cathode 25 and the plate, and a second source of direct current connecting the opposite end of the cathode with the control electrode, the said second source of direct current having its polarity reversed with respect to the first.
- 30 35 In testimony whereof I have hereunto set my hand.

FREDERICK S. McCULLOUGH.
